UNITED STATES PATENT OFFICE.

JOHN L. CREVELING, OF NEW YORK, N. Y., ASSIGNOR TO SAFETY CAR HEATING AND LIGHTING COMPANY, A CORPORATION OF NEW JERSEY.

ELECTRIC REGULATOR.

1,200,923.

Specification of Letters Patent. Patented Oct. 10, 1916.

Application filed December 11, 1909. Serial No. 532,615.

To all whom it may concern:

Be it known that I, JOHN L. CREVELING, a resident of New York, in the county and State of New York, have invented certain new and useful Improvements in Electric Regulators, as set forth in the annexed specification and drawing, forming a part thereof.

My invention pertains to that class of electric regulators adapted to control or regulate an electric circuit in a desired manner.

My invention has for its particular object to produce a simple and effective type of regulator which may be used to govern an electric circuit by varying the conditions therein in such manner as to produce a regulating effect.

In the drawing Figure I is a front elevation of one type of regulator comprehending my invention. Fig. II is a section of the regulator shown in Fig. I.

In the drawing 1 represents any suitable base of insulating material upon which my improved regulator is mounted.

2 represents the core of a suitable magnet, in this instance shown of the iron clad type provided with a magnetic jacket 3 and held firmly in place upon the base 1 as by the screw 4. The core 2 is surrounded by the winding 5 which may be wound upon a spool 6 as indicated. One end of the winding may be led as by the wire 7 to any suitable type of potential varying device as, for example, the variable resistance indicated at 8 which may be connected as by wire 9 with any suitable source of electro-motive force as indicated by the battery 10, the other side of which is shown as connected to the other end of the winding 5 as by the wire 11.

12 represents an armature of magnetic material in operative relation to the magnetic field set up by the winding 5. The springs 13 normally tend to push the armature 12 away from the magnet core 2 and the limit of travel which the springs are able to give the armature 12 is adjusted as by the nuts 14 upon the stud 15 which is of non-magnetic material and passes through a slip hole in the armature 12.

16 indicates steady pins of non-magnetic material which are fastened into the jacket 3 and free to slide in the holes 17 in the armature 12 in such manner as to prevent the armature from rotating. The armature

12 carries three arms indicated at 18 which are provided near their extremities with screws 19 which may be locked in place as by jam nuts 20. Upon the base 1 there are mounted three metallic or other conducting plates 21 with which electrical connection may be established as by means of studs 22. Upon these plates are set piles of contacting electrodes 23, the pressure upon which may vary their resistance as, for example, carbon plates or disks. These are held in place as by glass or other insulating tubes 24 secured to the base 1 as by means of screws 25. 65

26 indicates metallic or other conducting plates resting upon the contacting electrodes 23 and forming electrical connection therewith. Line connection with the said plates 26 may be established as by means of binding posts 27. The plates 26 are provided with insulating members 28 which form a mechanical connection between the screws 19 and the plates 26 and electrically insulate them therefrom. 70

29 represents any suitable source of electric current, in this instance indicated as a battery, the circuit of which it is desired to regulate by my improved regulator. 80

30 indicates the positive lead from the said source of electro-motive force 29 to one side of the lamps or other translating devices indicated at 31, the other side of which is connected as by wire 32 with the binding posts 27. From the binding post or stud 22 the wire 33 is carried to the opposite side of the source of electric current 29. 85

The operation of my improved electric regulator is substantially as follows: In practice, under certain conditions, I find it advisable to use three piles or units of resistance varying members, the resistance of which is varied by pressure for the reason that the pressure may be applied at a single point and with little difficulty equally distributed to the three resistance varying members. These resistance varying members, of course, may be connected either in series or multiple with each other or in separate circuits in accordance with the work to be performed by the regulator. However, as this connection will be obvious to one skilled in the art, for the sake of simplicity I have shown in the drawing only one of the resistance varying members electrically connected with a circuit it is desired to govern. The other members may be 100 105 110

connected to operate other circuits or in series with the one shown connected into the line or in multiple therewith if desired. If the battery 29 be considered as supplying the lamps 31 the current in the lamp circuit will, of course, pass through the pile of electrodes or other suitable resistance varying means 23 and may be governed by varying the resistance 23 which will be varied by the pressure thereon which in turn will be varied by the current in the winding 5 inasmuch as the magnetic field set up by the winding 5 will attract the armature 12 and if proper adjustment be given the screws 19 the pull upon the armature 12 will cause pressure to be applied to the resistance varying means 23 which pressure may thus be varied by varying the magneto-motive force of the coil 5. Any means for causing a desired variation in the magneto-motive force of the coil 5 may be employed and if the said coil be supplied with current from a source of electro-motive force as, for example, the battery 10 indicated in the drawing, the magneto-motive force of the coil 5 may be readily altered by altering the variable resistance 8 and if the resistance 8 be diminished more current will flow in the coil 5 and a greater pull will be exerted upon the armature 12 and a greater pressure applied to the resistance varying elements 23 and the resistance thereof varied. If these be carbon plates the resistance will decrease as the pressure is increased; therefore, if it be desired to increase the potential across the lamps 31 this may readily be done by decreasing the resistance 8 which will increase the pull upon the armature 12 and increase the pressure upon the carbon plates 23 and decrease the resistance thereof. If it be desired to decrease the potential across the lamps 31 the resistance 8 may be increased and the pull upon the core 12 lessened and the pressure upon the disks 23 lessened and the resistance thereof increased in such manner as to reduce the potential across the translating devices 31.

It is one of the usual inherent properties of a resistance varying element, in which the resistance is varied by changes of pressure, that if the element be subjected to very slight pressure a slight alteration in pressure will cause a considerable alteration in the resistance, whereas if the element be under considerable pressure a larger increase in pressure is necessary to cause an appreciable variation in resistance

and it will be obvious that with my improved regulator I am able to cause the pressure exerted upon the resistance varying element as, for instance the disks 23, to increase very rapidly per unit of change in the magneto-motive force of the coil 5 by properly adjusting the air gap between the magnet and the armature 12 for, if the air gap be small when the elements 23 are under the least pressure a slight movement of the armature 12 will cause the comparative length of the air gap to be greatly reduced and the pull exerted by the magnet upon its armature per ampere turn greatly increased inasmuch as the pull will vary approximately inversely as the square of the distance between the magnet and the armature.

I do not wish in any way to limit myself to the construction or exact mode of operation set forth in this drawing and specification as the same are intended merely to illustrate one type of regulator embodying the essentials of my invention and considerable alterations may be made without departing from the spirit and scope thereof.

Having thus described one form of embodiment of my invention, that which I consider novel and desire to protect by Letters Patent is as set forth in the following claim:

An electric regulator comprising an electromagnet having a core and a jacket; a plurality of resistance devices arranged around the magnet; an armature associated with the magnet and normally separated therefrom by a narrow air gap; arms carried by the armature and projecting therefrom, each of said arms engaging one of said resistances to exert pressure upon the same when the armature is attracted; resilient means between the magnet and the armature normally tending to move the armature away from the magnet; guiding pins carried by the jacket of the magnet and slidably engaging openings in the armature to steady the same; a stud carried by the magnet core and extending through an opening in the armature, said stud having means for limiting the movement of the armature away from the magnet; and a source of electricity and a manually adjustable resistance in circuit with said magnet to vary the strength of the same.

JOHN L. CREVELING.
